DESIGN FOR A BATTERY TESTER

Lawrence A. Blazey, Cleveland, Ohio, assignor to
Benjamin F. W. Heyer, Tenafly, N. J.

Application November 14, 1939, Serial No. 88,253

Term of patent 7 years

To all whom it may concern:

Be it known that I, Lawrence A. Blazey, a citizen of the United States, residing at Cleveland, in the county of Cuyahoga and State of Ohio, have invented a new, original, and ornamental Design for a Battery Tester, of which the following is a specification, reference being had to the accompanying drawing, forming part thereof.

The drawing is a view in perspective of a battery tester embodying my new design.

The rear of the lower portion is substantially the same as the front while the rear of the upper portion is enclosed.

I claim:

The ornamental design for a battery tester, as shown and described.

LAWRENCE A. BLAZEY.
